UNITED STATES PATENT OFFICE.

ALBERT M. BULLARD, OF NEW YORK, N. Y., ASSIGNOR TO WESTERN ELECTRIC COMPANY, OF CHICAGO, ILLINOIS, A CORPORATION OF ILLINOIS.

AUTOMATIC-EXCHANGE CIRCUIT.

No.838,006.

Specification of Letters Patent.

Patented Dec. 11, 1906.

Application filed March 10, 1906. Serial No. 305,287.

To all whom it may concern:

Be it known that I, ALBERT M. BULLARD, a citizen of the United States, residing at New York, in the county of New York and State of New York, have invented a certain new and useful Improvement in Automatic-Exchange Circuits, of which the following is a full, clear, concise, and exact description:

My invention relates to a telephone-exchange system wherein both manual and automatic exchanges are employed to unite a subscriber of the manual exchange with a subscriber of the automatic exchange. In the operation of such a system it often becomes necessary for the automatic-exchange subscriber, who has been called through the medium of a selector associated with a trunk-line leading to a neighboring manual exchange, to signal the manual-exchange operator who supervises the connection in order to make a complaint or give an order to such operator; and the object of my invention is to provide a system wherein an automatic subscriber who has been called by the manual-exchange operator and whose line is connected with the operator's cord-circuit may readily signal such operator over the trunk-line connecting his line with the manual operator's cord-circuit. In systems of this character heretofore in use it has been impossible for a called automatic subscriber to signal the manual operator with whose cord-circuit his line is connected, except where a number of trunk-lines lead from the automatic exchange to the manual exchange, in which case the called subscriber can select an idle trunk-line by operating his individual line-selector. If, however, there is but one trunk-line connecting the exchanges, a called automatic-exchange subscriber wishing to communicate with the manual-exchange operator could not signal her, for if he operates his line-selector to make connection with the terminals of the trunk-line thereon he will be locked out therefrom and receive a busy-signal, because the desired line—that is, the trunk-line—has effected a selective operation by means of its selector, and has therefore put the busy test on its multiple terminals, thus locking out all automatic subscribers, including the one connected with said selector so far as reverse signaling is concerned.

With my plan the automatic called subscriber is provided with a key at his station,

which when depressed causes ringing-current to be applied directly to the trunk-line to operate a signal at the manual exchange. To this end I connect a normally resting contact of the line-selector arm of each subscriber (which selector is of course idle when its line is called) with one of its terminals upon the trunk-selector, a condenser being included between said connection and the called line. The ringing-key when operated causes pulsating ringing-current to be connected with the selector-arm of such called line, and this current passes over the trunk-line and through the signal device at the manual exchange without being called upon to traverse any condensers at the automatic exchange which would interfere with proper operation of the signal and without affecting, due to the condenser referred to, the bells of any other stations which might be connected with the called subscriber's line.

I will describe my invention by reference to the accompanying drawing, which is a diagram representing a telephone-exchange embodying my invention.

The manual exchange A is provided with a spring-jack *a*, forming the terminal of a trunk-line extending in two limbs 1 2 to its multiple terminals 1^a 2^a at the automatic exchange B, normally open branches 1^b 2^b leading from conductors 1 2 to the selector-arms *b*¹ *b*² of the trunk-selector *b* at the automatic exchange B, said selector having terminals *b*¹ *b*² of all the lines in the automatic exchange. As shown, a selector is provided for each limb of the trunk-line; but in practice a single selector would be employed, comprising a contact-arm carrying a pair of contacts adapted to trail over the line-contacts.

At the manual exchange the operator is provided with a pair of link conductors 3 4, terminating in a plug *a'*, which is adapted to be inserted within jack *a* to unite said link conductors with the trunk-line, link conductor 4 including an interrupter C for operating the trunk-selector *b* to make connection with any desired automatic subscriber, and a ringing-key D for applying ringing current to the called automatic subscriber. An electromagnetic signal device F is provided in a bridge of the link conductors.

At the automatic exchange the trunk-line is provided with a bridge 5, including a grounded battery E, having its free pole con-

- nnected with trunk-conductor 1. A pair of relays *c* is included in said bridge between the battery and trunk-conductors 1 2, respectively, relay *c* controlling the operation of the stepping and retaining magnets *d d'* of the selector *b*. A conductor 6 extends from the free pole of battery *E* through armature *c*² of relay *c*' and its normally open front contact through normally closed contacts *e'* of a test-relay *e*, through the retaining and stepping magnets *d d'* in series, through the armature *f'* and its back contact of cut-off relay *f*, through the armature *c*³ and its back contact of relay *c*, to the grounded pole of battery *E*. The cut-off relay is included in a branch conductor 7, connected with conductor 6 between the stepping-magnet and armature *f'*, said conductor 7 being connected with the grounded pole of battery *E*.
- 20 The stepping-magnet is provided with an armature *d*², adapted when attracted to advance a ratchet-wheel *d*³, the shaft whereof carries the contact-springs *b' b'*, and the armature *d*⁴ of the retaining-magnet carries a 25 detent adapted when said armature is attracted to hold the ratchet-wheel in its advanced position.

The interrupter *C* comprises a controller-arm *g*, loosely mounted on a shaft and adapted to be moved forward against the tension of a suitable spring and when released to rotate a ratchet-wheel *g'* a distance corresponding to the forward movement of the arm. Said arm when away from normal position 35 severs the connection between link conductors 3 4 and connects conductor 4 with a contact *g*², adapted to be alternately connected with a grounded contact *g*³ by the movement of said ratchet-wheel. When plug *a'* is inserted into jack *a*, a metallic circuit is completed, extending from the positive pole of battery *E*, over conductor 5, through relay *c*, trunk-conductor 1, to the manual exchange, link conductor 3, through the windings of a 40 repeating-coil and impedance-coil to link conductor 4, and back by way of conductors 2 5 to the negative pole of the battery *E*, conductor 5 including relay *c*'. The operator at the manual exchange may now step the selector-springs *b' b'* into engagement with the desired line-terminals by operating her interrupter *C*, which opens the circuit of trunk-limb 1, rendering relay *c* inert, and applies a number of ground connections by springs *g*² *g*³ to 45 trunk-conductor 2 corresponding to the number of the line wanted. Each time a ground is thus applied a circuit is completed from grounded contacts *g*² *g*³, over link conductor 4, trunk conductor 2, conductor 5, including 50 relay *c*', to the free pole of grounded battery *E*. Each time the relay *c*' is thus energized it completes a circuit 5 6 5 to operate the stepping and retaining magnets and advance the arms *b' b'*. When the arm comes to rest 55 upon the desired terminals, the interrupter

returns to zero and restores the connection of conductors 3 4. The relay *f* is now energized in a circuit 5 6 7 5, said relay being short-circuited by the back contact of armature *C*³ during selection. When said relay is energized, it completes at its armature *f*² and front contact the continuity of conductor 2^b, which thereupon connects conductor 2 directly with its selector-arm *b*, while its armature *f*³ extends conductor 8, which is connected with a source of ringing-current, through armature *c*⁴ of relay *c*' to the back contact of armature *c*⁵ of relay *c*, said armature *c*⁵ being included in conductor 1^b and connected directly with one arm *b'* of selector *b*. The selector-arms while away from normal position disconnect the multiple terminals 1^a 2^a from the trunk-line and apply busy test to terminals 2^a, also continuing the connection of conductor 1 through a portion 85 of conductor 1^b the front contact of armature *c*⁵ of relay *c*.

In case the line wanted had been busy a test potential would have been found on the terminals of the line to which selector-arm of 90 limb 2 is connected and a current would pass over conductor 2^b to armature and back contact of cut-off relay *f*, said back contact being connected with a conductor 9, leading through a quick-acting test-relay *e*, through the armature *c*³ and front contact of relay *c* to earth. Said relay *e* would thereupon become energized before the sluggish relay *f* had time to respond and open at its contacts *e*, the circuit of the stepping and retaining magnets, causing the selector-arms to return to zero, said relay *e* also applying at its contacts *e'* a busy-test current to the trunk-line.

Let us assume that the trunk-selector has completed connection with line 60, the terminals whereof are connected by conductors 10 11 with the station of such line. The operator at exchange *A* now operates her ringing-key *D*, which severs the connection of link conductors 3 4 and grounds conductor 4, thereby rendering relay *c* inert and causing relay *c*' to remain energized. The conductor 8, including the source of ringing-current, is now connected directly with the portion of conductor 1^b connected with selector-arm *b'*, and ringing-current passes over conductors 8, 1^b, and 10, through the called-subscriber's bell, and back over limb 11, conductors 2^b 5 to ground.

The telephone-line 60 is provided at the 120 central office with a selector *k* and mechanism similar to that associated with the trunk-line, relays *h h'* and a battery *E'* being included in a bridge 5^a of the conductors 10 11, a condenser *i* being interposed in conductor 11 between bridge 5^a and the line-terminal, and a condenser *i'* being included in conductor 1^b; so that the two lines have independent talking-current supplies.

The selector-arm *k'* of limb 10 of line 60 is 130

connected with a conductor 8^a, which extends through armature h⁴ and its front contact of relay h', armature l³ and its front contact of cut-off relay l of the line, to a source 5 of grounded pulsating ringing-current G, while the first contact of the line-selector, which has heretofore been unused electrically, being simply a dead terminal, is connected by a conductor 12 with conductor 11 10 between the terminal of the line on the trunk-selector and condenser i.

When the subscriber at station 60 in response to the manual operator's call removes his telephone, relays h h' are included in a metallic circuit 5^a 10 11 5^a, including battery E', and are energized. Relay h' in attracting its armature h² closes a circuit 5^a 6^a 7^a 5^a for relay l. Now if the subscriber at station 60 should at any time during the connection desire to signal the operator at the manual exchange he operates his ringing-key D', which opens conductor 10, causing relay h to retract its armature and connects limb 11 to ground, whereupon a circuit from the free 20 pole of grounded battery E' is completed for relay h' by way of conductors 5^a 11 to earth. Relay h being inert and relays h' and l energized, conductor 8^a is completed and ringing-current from the source G flows over the following path: Conductor 8^a, selector-arm k', which is resting on its normal contact, conductor 12, limb 11 of the line 60, contacts b² b' of the selector, conductors 2^b 2 of the trunk-line, link conductor 4 through the operator's signal F and back over link conductor 3, trunk-conductor 1, bridge 5, to ground. Thus no condensers are interposed in the ringing-circuit in series with the condenser in series with the operator's signal, while the 40 condenser i, necessarily in the line-circuit, is interposed in series with the bells of other stations of line 60, resulting in the operation of the said signal and the non-operation of the said bells.

45 The limb 10 is normally disconnected from its selector-arm k' at contacts m m', which are connected when the selector-arm is away from normal position. This prevents a low-resistance shunt upon the line 60 by way of arm k', its normal contact and conductor 12, when the relay h is energized.

I claim—

1. The combination with a manual telephone-exchange, of an automatic exchange, a number of telephone-lines extending from substations to said automatic exchange, a trunk-line extending between said exchanges, a signal device adapted to be connected with said trunk-line at the manual exchange, a selector for the trunk-line at the automatic exchange, means controlled from the manual exchange for operating said selector to connect said trunk-line with any one of said telephone-lines, a ringing-key at the substation of said called line and means controlled

by said key for applying current to said trunk-line, to operate said signal device.

2. The combination with a manual telephone-exchange, of an automatic telephone-exchange, a number of telephone-lines extending from substations to said automatic telephone-exchange, a selector for each line at the automatic exchange for connecting said line with another line in said exchange, a trunk-line extending from the manual exchange to the automatic exchange, an electromagnetic signal adapted to be connected with the trunk-line at the manual exchange, a selector connected with the trunk-line at the automatic exchange adapted to connect 70 said trunk-line with any one of said telephone-lines, a source of ringing-current, a ringing-key at the called station, and means controlled by said key and the called-subscriber's selector for applying ringing-current 75 from said source to the trunk-line to operate said signal device.

3. The combination with a manual telephone-exchange, of an automatic exchange, a number of telephone-lines extending from substations to said automatic exchange, a selector for each line at the automatic exchange, said selector comprising a contact-arm controlled from the station of said line, and adapted to sweep over the terminals of 90 the other lines to connect said line with a desired line, a trunk-line extending from the manual exchange to the automatic exchange, an electromagnetic signal device at the manual exchange adapted to be connected with 95 said trunk-line, a selector connected with said trunk-line in the automatic exchange adapted to connect said line with the terminal of any line in the exchange, a conductor extending from the normal resting contact 100 of each line-selector to the terminal of such line upon the trunk-selector, a source of ringing-current, and means controlled from the station of a line with which such trunk-line is connected for connecting said source of ringing-current with the individual selector-arm of such line to operate said electromagnetic signal device at the manual exchange.

4. The combination with a manual telephone-exchange, of an automatic exchange, 115 a number of metallic circuit telephone-lines extending from substations to said automatic exchange, a selector for each line at the automatic exchange comprising an arm carrying contacts of said line and adapted to 120 sweep over the terminals of the other lines to connect said line therewith, a metallic circuit trunk-line extending from the manual exchange to the automatic exchange, an electromagnetic signal device adapted to be connected with the trunk-line at the manual exchange, a selector at the manual exchange having contacts on its movable arm connected with said trunk-line, terminals on said selector connected with said telephone-lines, 125 130

a grounded source of current connected with the trunk-line, electromagnetic mechanism responsive to current from said source controlled from the manual exchange for operating the trunk-selector to connect the trunk-line with the terminals of a desired line, condensers interposed between the limbs of the trunk-line and the limbs of the called line, a conductor connecting the normal resting terminal of one contact of the selector-arm of a called line with one of its terminals upon the trunk-selector, a source of grounded ringing-current, and electromagnetic mechanism controlled from the called station for connecting said source of ringing-current with said selector-arm contact to operate the signal device at the manual exchange.

5. The combination with a manual telephone-exchange, of an automatic exchange, a number of metallic circuit telephone-lines extending from substations to said automatic exchange, a selector for each line at the automatic exchange comprising an arm carrying a pair of contacts and adapted to sweep over the terminals of the other line to connect its line therewith, a metallic circuit trunk-line extending from said manual exchange to the automatic exchange, an electromagnetic signal device adapted to be connected in a bridge of the trunk-line at the manual exchange, a selector at the automatic exchange having contacts on its movable arm connected with said trunk-line, terminals upon said selector connected with the said telephone-lines, a relay with a source of grounded current in a bridge of the trunk-line at the automatic exchange adapted to operate said trunk-selector under the control of the man-

ual operator to connect the trunk-line with the terminals of a called line, a source of current in a bridge of the called line, a relay in said bridge, condensers in the limbs of said connected circuits between the said bridges, a conductor extending from the normal resting terminal of one contact of the selector-arm of each subscriber's line to a terminal of one limb of such line upon the trunk-selector, the condenser in such line being located between the connection of such conductor therewith and the called line, a source of grounded ringing-current, and a key at a called station for operating the relay in its bridge at the exchange, to apply current from said source to said selector-arm contact of such line to operate the signal device at the manual exchange.

6. The combination with a manual telephone-exchange, of an automatic telephone-exchange, a number of telephone-lines extending from substations to said automatic exchange, a selector for each line at the automatic exchange, a trunk-line extending between said exchanges, a signal associated with the trunk-line at the manual exchange, a selector at the automatic exchange adapted to connect said trunk-line with any one of said telephone-lines, and means controlled from a substation of the line with which said trunk-selector makes connection, and by the individual selector of said called line, for operating said signal.

In witness whereof I hereunto subscribe my name this 5th day of March, A. D. 1906.

ALBERT M. BULLARD.
